SASH WINDOW

Sam Maurer, Burnaby, British Columbia, Canada, assignor of thirty-five per cent to Emil Wuschke, South Burnaby, British Columbia, Canada, and thirty-two and one-half per cent to Paul A. Seidel, Vancouver, British Columbia, Canada.

Application May 5, 1934, Serial No. 724,173
Renewed May 23, 1935

9 Claims. (Cl. 20—49)

My invention relates to improvements in sash windows which are particularly adapted for windows of the double hung sash type. The objects of the invention are to provide means for hanging a window sash whereby it may be raised and lowered in the usual way and swung about a horizontal axis, so as to afford ventilation or to facilitate cleaning of the outside of the sash pane, and to provide also a means for preventing draught between the sash stiles and the window frame.

The invention consists of a pair of sheet metal strips folded longitudinally and adapted to be secured to the stiles of a window sash and capable of being compressed transversely to allow the sash to swing about a horizontal axis, as will be more fully described in the following specification and shown in the accompanying drawing, in which:—

Fig. 1 is an elevational view of one strip slidably mounted in the pulley stile of a window frame.

Fig. 2 is a vertical sectional view.

Fig. 3 is a sectional view taken on the line 3—3 of Figure 2.

Fig. 4 is a transverse sectional view of a strip reinforced as for use with heavy sashes.

In the drawing like characters of reference indicate corresponding parts in each figure.

The numeral 1 indicates a pulley stile of a double hung sash window which is provided with stops 2, fitted in the usual way, a sill 3 and a stool 4.

The numeral 5 indicates a sash consisting of stiles 6, bottom rail 7 and meeting or top rail 8. The width of the sash 5 is slightly less than the opening between stops 2 of opposite pulley stiles 1.

Each sash is provided with a concave groove 9, see Figure 3, the purpose of which will herein-after appear. Pivotally mounted within each groove 9 is a strip 10, which is preferably made of sheet spring brass and is transversely bent to a substantially oval form with folds 11 and 12 connected together by a bead 13. The free end of the fold 12 is inturned to provide a further bead 14 which with the bead 13 serves to engage the stops 2 of the pulley stile and keep the strip in place therein.

Housed within the strip 10 is a semi-elliptical spring 15 which bears, adjacent its ends as at 16, against the fold 12 and is held in place within the strip by a screw 17 which passes through an orifice in the fold 12 and into the stile 6 of the sash. It is preferable that the central portion of the spring 15 shall bear against the fold 11 of the strip as shown in Figures 2 and 3, but this

is not essential. The upper end of the spring 15 is bent over to form a hook 18 to which a sash cord 19 is connected.

At the upper end of the fold 12 a rectangular gap 20 is formed, and secured to the fold by a slack rivet 21 is a spring 22 having an overhanging latch or projection 23 at its upper end, which is adapted normally to pass through the gap 20 and engage a corresponding slot 24 formed in the upper end of the sash stile 6 to prevent the sash from being inadvertently swung about the pivot screws 17. This spring is adapted, on the pressing back of its latch 23, to be swung about the rivet 21 and to assume an inclined position as shown in Figure 1, with the latch engaged on the inner side of the fold 12, so as to hold it out of engagement with the sash and to permit the sash to be swung.

In the modification shown in Figure 4, the fold 12 of the strip is reinforced with a transversely curved strip 25 which conforms to the normal extended curvature of the fold 12.

In use the sash can be raised and lowered in exactly the same manner as in the conventional type of double hung sash window.

When it is desired to swing the sash either for ventilation or to reverse it to clean its outer glass surface, the latch 23 is pressed towards the pulley stile 2 and is then thrust over to one side of the gap 20, thus locking it against return movement, then the top or bottom rails 7 or 8 respectively are pulled inwardly, which action, due to the curvature of the grooves 9 in the sash stiles causes the fold 12 of the strip 10 and the spring 15 to be compressed so that the sash may turn about the axis of the screw 17. When the sash is tilted out of the vertical, the pressure exerted upon it by the inherent spring of the strip and of the spring 15 prevents the strips from sliding, except under undue force, so that the horizontal axis of the sash will remain undisturbed.

Where heavy sashes are to be slidably and pivotally hung, the reinforcing strip 25 is desirable, since substantially the same strength of spring is required in all strips irrespective of weight of each, but then in heavy sashes, when swung out of the vertical there is a tendency for the upper and lower ends of the strip to project beyond the centre portion, hence by reinforcing said strip with a further concave strip 25, the vertical face of both is maintained in a straight vertical line.

What I claim as my invention is:

1. A window sash mounting comprising a strip of sheet material folded longitudinally into two

2. A window sash mounting comprising a strip of sheet material folded longitudinally into two folds, the intersection of the folds forming a bearing bead and the free end of one of the folds being bent to form a complementary bead, said fold having a longitudinal convex curve adapted to frictionally engage the stile of a sash and being adapted for pivotal mounting upon said stile, the other of said folds being adapted to slidably engage the pulley stile.

3. A window sash mounting comprising a strip of sheet material folded longitudinally into two folds, the borders of the folded strip being provided with beads adapted to slidably engage the stops of a pulley stile, means formed integrally with one of the folds for frictionally engaging the stile of a sash, said strip being adapted for pivotal mounting upon said sash stile, and the other of said folds being adapted to slidably engage the pulley stile.

4. A window mounting comprising a strip of sheet material folded longitudinally into two folds, one of said folds being transversely curved to engage a complementary groove in a sash stile, and spring means other than the inherent spring of the sheet material for urging the folds apart.

5. A window mounting comprising a strip of sheet material folded longitudinally into two folds, one of said folds being transversely curved to engage a complementary groove in a sash stile, and spring means other than the inherent

folds separated at their free ends, one of said spring of the sheet material for urging the ends of the curved fold away from the other fold.

6. A window mounting comprising a strip of sheet material folded longitudinally into two folds, one of said folds being transversely curved to engage a complementary groove in a sash stile, and a semi-elliptical spring extending longitudinally between said folds for urging them apart.

7. A window mounting comprising a strip of sheet material folded longitudinally into two folds, one of said folds being transversely curved to engage a complementary groove in a sash stile, and a semi-elliptical spring extending longitudinally between said folds for urging them apart, said spring being provided at one end with means for attachment to a sash cord.

8. A window sash mounting comprising a strip of sheet material folded longitudinally into two spaced folds, one of said folds being provided with a transverse curve convex exteriorly of the strip, the upper end of said strip being provided with a gap, and a spring latch secured to the inside of the fold and to project outwardly through said gap.

9. A window sash mounting comprising a strip of sheet material folded longitudinally into two spaced folds, one of said folds being provided with a transverse curve convex exteriorly of the strip, the upper end of said strip being provided with a gap, and a spring latch secured to the inside of the fold and to project outwardly through said gap, said latch being pivotally mounted whereby the latch can be sprung rearwardly through the gap and moved transversely to engage a border of the gap to lock it out of action.

SAM MAURER.
